UNITED STATES PATENT OFFICE.

ISAAC GORDON, OF SCHENECTADY, NEW YORK.

GAS WATER HEATER.

Application filed August 21, 1922. Serial No. 583,429.

To all whom it may concern: -

Be it known that I, ISAAC GORDON, a citizen of the United States, and a resident of Schenectady, in the county of Schenectady and State of New York, have invented certain new and useful Improvements in Gas Water Heaters, of which the following is a full, clear, and exact description.

The invention relates to a gas water heater which is adapted to be operated in conjunction with a single, double or other gas burner in any type of gas range, gas cooker, gas and coal combination range, or gas heater.

One of the objects of the invention is to provide a device of this character which will provide hot water while the burner is being used for cooking or baking purposes, thereby not only adding to the usefulness of the range, etc., and saving the space and expense of a separate water heater, but also greatly reducing the consumption of gas.

Another object of the invention is to provide a water heater of this character so constructed that it in no way interferes with the direct application of the burner heat to the cooking vessel; but, on the contrary, the construction of the water heater is such that it really assists in applying the heat to the cooking vessel and reduces the loss of heat by radiation.

Further objects and advantages of the invention will be apparent from the following detailed description when taken in connection with the accompanying drawings, in which:

Figure 1 is a perspective view of the water heater and burner detached from the range.

Figure 2 is a vertical sectional view of the water heater and burner.

Figure 3 is a plan view of a range with the water heater applied thereto.

Figure 4 is a rear elevation of a range and showing the connections between the water heater and tank.

Figure 5 is a perspective view of a modified form of the water heater.

Referring to the drawings more in detail, numeral 1 indicates a double gas burner composed of two circular pipes 2 and 3, the upper pipe being preferably provided with holes arranged to direct the gas horizontally or at 45° to the horizontal, while the lower pipe is preferably provided with holes arranged to direct the gas vertically or at 45° to the horizontal. The arms supporting the upper circular pipe are also provided with

holes arranged in the top thereof, as clearly shown in the drawings. The burner may be supplied by a single gas pipe, but I prefer to employ separate gas pipes, and I have, therefore, illustrated the gas supply pipe 4 associated with the circular burner 2 and gas supply pipe 5 associated with burner 3; it being understood, of course, that an independent valve is employed for each supply pipe.

The water heater, in the preferred embodiment of the invention, is a hollow, annular, one-piece member 6, having appropriate connections, to be hereinafter described, for the circulation of water. While I have shown the walls of the water heater as vertical, it will be understood that the inner wall may be inclined, if so desired. It is also to be noted that, instead of being annular, the water heater may be of any desired shape; for instance, it may be oval or rectangular, etc. The relative arrangement between the burner and the water heater is clearly illustrated in Figs. 1 and 2; the arrangement being such that the water heater is almost directly over the lower circular burner, while the upper circular burner is within the water heater. The water heater may be mounted in place on the gas stove, gas heater, etc., in any desired manner, but I have illustrated hangers or brackets 7 which are attached to the under side of the top of the gas range, as shown in Fig. 3. The position of the heater with respect to a range is also shown in dotted lines in Fig. 4.

It may be noted here that the invention is not limited to use with any particular type of burner and its use is contemplated with any type of burner; as, for example, the star burner indicated by numeral 8 in Fig. 3.

The means for circulating the water is best illustrated in Fig. 4. The pipe 9 supplies water to the tank 10, and the water is carried from the bottom of the tank to the water heater by the pipe 11, while the pipe 12 carries the hot water from the water heater to the tank, thereby completing the circulation. It is to be noted here that the cold water pipe 11 connects with the lower portion of the water heater, while the hot water pipe 12 connects with the upper portion thereof, thus assuring a proper circulation of the water.

In place of the water heater described above I may prefer to employ a coil water

heater 13, illustrated in Fig. 5. The arrangement of the coil water heater, with respect to the burner, is the same as in the ring member 6, and any detailed illustration or description is believed to be unnecessary.

In operation with a range, the burner is lighted, and a cooking utensil is placed on the range in the usual manner. Ordinarily it will only be necessary to employ the upper circular pipe 2, and the flames from this burner striking against the wall of the water heater will rapidly heat up sufficient water for ordinary purposes; and at the same time the water heater acts as a hood or heat concentrator to confine the heat within the space defined by its wall and cause it to be applied to the cooking vessel. It is thus apparent that by the use of my invention there is a great saving in space and expense by eliminating the separate water heater; and, further, that the relative arrangement between the burner and water heater is such that all of the heat developed is employed for a useful purpose, thereby eliminating to a large extent the heavy loss of heat which in prior constructions merely raised the temperature of the surrounding atmosphere.

30 In the event that an unusual amount of hot water is required, it is only necessary to light the lower burner, which is so located that the heat therefrom is applied almost directly to the bottom of the water heater.

35 Where my water heater is employed with a gas heater or other device, except a range, the cooking vessel may be mounted directly on the water heater, and it is to be understood that my invention contemplates such

40 use.
In accordance with the patent statutes, I have described what I now believe to be the best embodiment of the invention, but I do not wish to be understood thereby as limiting myself or the scope of the invention, as many changes and modifications may be made without departing from the

spirit of the invention; all such I aim to include in the scope of the appended claims.

What I claim as new and desire to secure by Letters Patent is:

1. A heating system, including an annular water heater for use with gas ranges, gas heaters and the like, the inner and outer walls of the heater being substantially vertical, an annular gas burner arranged wholly within the water heater and adapted to project the flame against the inner wall of the water heater, and a second annular gas burner arranged substantially directly beneath the annular bottom wall of the water heater.

2. A heating system, including an annular water heater for use with gas ranges, gas heaters and the like, the inner and outer walls of the heater being substantially vertical, an annular gas burner arranged wholly within the annular water heater and adapted to project the flame against the inner wall of the water heater, a second annular gas burner arranged substantially directly beneath the annular bottom wall of the water heater, separate means for controlling the two burners, and water circulating pipes connected with the upper and lower portions of the water heater.

3. A heating system, including an annular water heater adapted to support a cooking vessel, the inner and outer walls of the heater being substantially vertical, an annular gas burner arranged wholly within the annular water heater and adapted to project the flame against the inner wall of the water heater, a second annular gas burner arranged substantially directly beneath the annular bottom wall of the water heater, separate means for controlling the two burners, a water tank, a pipe leading from the lower portion of the tank to the lower portion of the water heater, and a pipe leading from the upper portion of the water heater to the upper portion of the tank.

ISAAC GORDON.
